UNITED STATES PATENT OFFICE

145,983

DESIGN FOR A SHRINE

Allen S. Powell, Wilkes-Barre, Pa.

Application April 2, 1946, Serial No. 128,203

Term of patent 14 years

(Cl. D29—23)

To all whom it may concern:

Be it known that I, Allen S. Powell, a citizen of the United States, residing at Wilkes-Barre, in the county of Luzerne and State of Pennsylvania, have invented a new, original, and ornamental Design for a Shrine, of which the following is a specification, reference being had to the accompanying drawings, forming a part thereof.

I claim:

The ornamental design for a shrine, as shown.

ALLEN S. POWELL.
